OR D19,545 EX

DESIGN.

G. S. BARKENTIN.

ORNAMENTATION OF BUILDERS' HARDWARE.

Patented Dec. 31, 1889.

UNITED STATES PATENT OFFICE.

GEORGE S. BARKENTIN, OF NEW BRITAIN, CONNECTICUT, ASSIGNOR TO P.
& F. CORBIN, OF SAME PLACE.

DESIGN FOR THE ORNAMENTATION OF BUILDERS' HARDWARE.

SPECIFICATION forming part of Design No. 19,545, dated December 31, 1889.

Application filed October 30, 1889. Serial No. 328,710. Term of patent 7 years.

To all whom it may concern:

Be it known that I, GEORGE S. BARKENTIN, a citizen of the United States, residing at New Britain, in the county of Hartford and State 5 of Connecticut, have invented and produced a new and original Design for the Ornamentation of Builders' Hardware, of which the following is a specification, reference being had to the accompanying drawings, forming part 10 thereof.

Figure 1 is a face view of a knob and escutcheon-plate having my design of surface ornamentation thereon, and Fig. 2 is a like view of a push-button and escutcheon-plate 15 on which is placed my design for surface ornamentation.

The invention relates to surface ornamentation of builders' hardware, including the knob, the key-hole and knob escutcheons, the face- 20 plate or front of the latch, sash-lifts, hinges, and other articles.

The leading feature of my design consists in the surface ornamentation of the panels or other faces on articles of builders' hardware 25 by figures consisting of intermingled conventional leaves, scrolls, and faces.

In both figures, *a* designates figures representing human faces, and *b* the leaf and scroll figures, the same intermingling with each other 30 and a part of them extending from the faces, as shown. The principal panels or faces—as, for instance, the knob-front *A* and the major panel in the escutcheon-plate *B*—are each surrounded by rows of beads *d*. Surrounding this bead-border on each escutcheon-plate 35

is a plain border *e*, and outside of this is a border *f*, composed of alternate scrolls and beads. Each escutcheon-plate is provided with a crown or cap *C* and a base *D*, the design of which is in harmony with that al- 40 ready described. Each of the faces is combined with the scrolls and leaves, so as to represent what might be termed "conventional crowns and beard," as shown.

What I claim is—

1. The design for the surface ornamentation of builders' hardware herein shown and described, the same comprising the figures of faces and intermingling leaf and scroll figures surrounded by a bead-like border, the 50 plain border, and the border of alternate beads and scrolls, as set forth.

2. In the design for surface ornamentation of builders' hardware herein shown and described, the surface ornamentation of the 55 panel-ground, comprising the figures of human faces and intermingling leaf and scroll figures, forming conventional crowns and beard, as set forth.

3. In the design for the surface ornamentation of builders' hardware herein shown and described, the surface ornamentation of the 60 panels, comprising the intermingling leaf and scroll figures and a surrounding border of beads *d*, as set forth.

GEORGE S. BARKENTIN.
